UNITED STATES PATENT OFFICE.

REINHOLD H. WAPPLER, OF NEW YORK, N. Y., ASSIGNOR TO AMERICAN CYSTOSCOPE
MAKERS, INC., OF NEW YORK, N. Y.

DIAGNOSTIC LAMP.

1,087,998.

Specification of Letters Patent.

Patented Feb. 24, 1914.

Application filed August 21, 1913. Serial No. 785,351.

To all whom it may concern:

Be it known that I, REINHOLD H. WAPPLER, a citizen of the United States, residing at New York city, county and State of New York, have invented a new and Improved Diagnostic Lamp, of which the following is a specification.

This invention relates to a novel electric lamp for diagnostic purposes which may be readily adapted to the peculiar location of the organs to be examined. The lamp is more particularly designed to be used in conjunction with a direct vision ophthalmoscope of novel construction, and embraces other novel features more fully brought out in the specification and appended claims.

In the accompanying drawing: Figure 1 is a longitudinal section through my novel diagnostic lamp showing the ophthalmoscope in position; Fig. 2 a rear view of the ophthalmoscope and part of the holder; Fig. 3 a sectional side view of Fig. 2; Fig. 4 a side view of the lamp, showing the parts in a different position, and Fig. 5 a plan of Fig. 4.

My improved lamp comprises essentially a cylindrical metallic casing 10 that constitutes a handle. Casing 10 is closed at its ends by screw caps 11, 12 and is shown to contain a pair of dry cells 13, a cylindrical insulator 14 being preferably interposed between the casing and cells. Cells 13 are held in contact with each other by a spring 15 that simultaneously serves for connecting the lower pole of the lower cell with a cap 11 and consequently with casing 10. Into a tubular extension of cap 12 is tapped an insulating tube 16, into which is, in turn, tightly fitted a metallic plug 17, the latter being in contact with the upper pole of the upper cell 13. Plug 17 is provided with an axial socket 18 and with a transverse bore 19 of like diameter, bore 19 also extending through tube 16. Into either socket 18 or bore 19 is adapted to be inserted the stem 20 of a hollow conductive rod or light holder 21. The latter is in turn firmly set into one end of a coupling 22, into the other end of which is fitted the stem 20 by means of an intervening insulating tube 23. Irrespective as to whether stem 20 has been introduced into socket 18 or bore 19, the stem may be fixed in position by one and the same clamp screw 24. Into the free end of rod

21 is tapped the socket 25 of an electric light bulb 26. One pole of said lamp is in direct conductive connection with socket 25 and consequently with rod 21 and coupling 22, while its other pole is, by wire 27, connected to stem 20. On coupling 22 is rotatably mounted a ring 28 provided with a contact spring 29, the free end of which is normally spaced from cap 12. If it is desired to light bulb 26, handle 10 is grasped preferably by means of an insulating cylindrical grip 30 surrounding said handle, and spring 29 is then pressed against cap 12. In this way a circuit is closed, the current flowing from cells 13 through plug 17, stem 20, wire 27, bulb 26, socket 25, holder 21, coupling 22, sleeve 28, spring 29, cap 12, casing 10, cap 11, and spring 15 to cells 13.

Holder 21 is adapted to be telescoped by a tube or sleeve 31 which is partially split as at 32 and may be secured to holder 21 by clamp screw 33. Tube 31 is closed at its top as at 34 and is provided with a rear oblong aperture 35 through which the light may be emitted from bulb 26 as illustrated in Fig. 3. Tube 31 carries a block 36 to which a pair of spaced plates 37, 38 is secured, the plate 38 being provided with a shield 39. Plate 38 is further provided with a circular observation opening 40 the center of which approximately coincides with the top of tube 31 as clearly shown in Fig. 2. Intermediate plates 37, 38, there are accommodated a pair of disks 41, 42 which are rotatably secured to plate 37 by screw 43. Disk 41 is provided with one or more visual apertures 44 which may be brought into axial alignment with opening 40 by means of a pin 45 extending forwardly from said disk. The latter is accommodated within a forwardly projecting rim of disk 42, said disk having a plurality of apertures that are provided with magnifying lenses 46 of different focus, and may be successively brought opposite opening 40 by grasping the rim of disk 42. The number of the lens temporarily aligned with opening 40 may be ascertained by an index 47 which is adapted to be exposed through a corresponding opening 48 or disk 41 and through a slot 49 of plate 37.

It will be seen that upon pressing contact 29 against cap 12, and bringing the ophthalmoscope within the proper position, the op-

erator may unobstructedly view the eye of a patient or another object to be examined, through the upper half of opening 40, the light being thrown upon said object by bulb 26 through aperture 35.

It is obvious that the apparatus may also be used for inspecting certain inner parts of the human body, such as the interior of the ear, mouth, etc., for which purpose screw 33 is loosened and tube 31 together with the parts carried thereby, is removed from holder 21. If the location of the organ to be examined so requires, holder 21 may be withdrawn from socket 18 after loosening screw 24 and may be inserted into bore 19, so that its axis extends at right angles to that of handle 10 as clearly illustrated in Figs. 4 and 5. In order to prevent an accidental contact between spring 29 and cap 12 during shipment, etc., the insulating sleeve 30 the outer diameter of which exceeds that of the cap, is shifted up against the latter, as shown by dotted lines in Fig. 1.

25 I claim:

1. A diagnostic lamp comprising a holder, an incandescent bulb carried thereby, means for supplying electric current to said bulb, a sleeve removably fitted on said holder and having a lateral aperture near the free end thereof, said aperture being adapted to be brought into alignment with the bulb, and a disk carried by the sleeve and having an opening the center of which is located in

substantial alignment with the apertured end 35 of the sleeve.

2. A diagnostic lamp comprising a hollow conductive handle, a cell inclosed therein and having one of its poles connected to said handle, an insulated plug carried by the handle and having an axial socket and a transverse bore, said plug being conductively connected to the other pole of the cell, a holder adapted to be fitted either into the socket or into the bore, an incandescent bulb 40 carried by the holder, and means for conductively connecting said bulb to the casing and plug.

3. A diagnostic lamp comprising a hollow conductive handle, a cell inclosed therein and having one of its poles connected to said handle, an insulated plug carried by the handle and having an axial socket and a transverse bore, said plug being conductively connected to the other pole of the cell, a holder adapted to be fitted either into the socket or into the bore, an incandescent bulb 45 carried by the holder, means for connecting one pole of said bulb to the plug, means for connecting the other pole of the bulb to the holder, and a contact on the holder that is adapted to be brought into conductive engagement with the casing.

REINHOLD H. WAPPLER.
